UNITED STATES PATENT OFFICE

2,425,657

SHORT-WAVE APPARATUS

Harry Tunick, Rye, N. Y., assignor to Radio Corporation of America, a corporation of Delaware

Original application April 17, 1941, Serial No. 388,999. Divided and this application December 13, 1943, Serial No. 514,021

17 Claims. (Cl. 179—171.5)

1

This application is a division of my copending application Serial No. 388,999, filed April 17, 1941, now U. S. Patent #2,337,214.

My present invention relates to improvements in ultra short wave apparatus and particularly to apparatus useful for the production of frequency modulated waves. Generally, it is an object of my present invention to provide improved apparatus for the efficient generation and frequency modulation of waves of very short wave length.

In one form of my invention my improved apparatus comprises a space resonator having a gap. An electron discharge path is set up for providing a flow of electrons past the gap in such a way as to cause the resonator to be excited at high frequency. To produce the electron flow, there is provided an electron emitting cathode which is grounded, an anode which is maintained at a negative potential with respect to ground, and an intermediate electron permeable grid which is maintained at a positive potential with respect to ground. As will be explained more fully later, electrons oscillate through and about the positively charged grid and their simultaneous passage across the gap excites the resonator. In order to modulate the waves so generated and set up in the resonator, signal voltages are applied to the negatively charged anode. By appropriate adjustment of these voltages, it will be found that the arrangement will produce, over a useful range, linear frequency modulation substantially free of undesired amplitude modulation.

Various advantages, features and further objects of my invention will appear as the more detailed description thereof proceeds.

In the drawings:

Figure 1 illustrates one form of my invention for producing very short frequency modulated waves. The system employs a cavity resonator excited by an electron stream, one terminating electrode for which is varied in voltage so as to produce the desired frequency modulation.

Figure 2 is a modification in which an electron emitting surface has been used to replace the negatively charged anode of Figure 1;

Figure 3 illustrates diagrammatically still another modification of my invention; and

Figure 4 is a modified form of Figure 1.

Turning to Figure 1, I have provided a vacuum tube having an hermetically sealed, evacuated, cylindrical glass container 2. Within the tube 2 there is provided a cathode 4 at one base of the tube, a disc-like plate 6 at the other base of the tube 2, and intermediate these two electrodes

2

there is provided a perforated disc-like grid or control electrode 8. Grid 8 extends across the entire cross-section of tube 2. Cathode 4 is provided with a heater element 10 which may be energized by a suitable filament transformer 12 whose primary is connected to any suitable source, not shown. The cathode 4, as shown, is connected directly to ground or may be maintained at a small negative potential with respect to ground 10 by inserting a suitable biasing source in series with the ground lead 14. Similarly, the disc-like anode 6 may be connected to ground through a variable source of potential 16 which, preferably, is adjusted so as to subject the anode 6 to a negative potential with respect to ground 18. The grid 8 is connected by way of conductor 20 to potentiometer 22 in shunt to potential source 24. Tap 26 is so adjusted on potentiometer 22 as to cause the grid 8 to be subjected to a high positive potential.

As a consequence of the foregoing construction and connections, electrons are attracted from cathode 4 by the positively charged grid 8 and are given such velocity that they pass through grid 8 only to approach the negatively charged anode 6 which now serves to slow up the electrons and repel them. In addition, after the electrons pass through the grid 8, the grid is now behind the electrons and tends to pull them back towards the cathode 4. It therefore follows that clouds of electrons are caused to oscillate through and about the grid 8.

By appropriately mounting a cavity resonator 28 about the tube 2, as shown, the pulses, clouds 35 or groups of electrons oscillating between cathode 4 and anode 6 and through grid 8 inductively excite the resonator 28. By appropriate choice of voltages impressed upon the anode 6 and the grid 8 and by appropriately choosing the size of 40 the gap 30 for the cavity resonator 28, as well as the dimensions of the cavity resonator 28, the electron cloud oscillations may be brought into synchronism with the resonant waves set up within the cavity oscillator, thereby producing 45 oscillations of extremely high frequency and relatively high power. Output energy may be taken inductively from the cavity resonator by means of the metal loop or conductor 32 insulatingly passed through the walls of the cavity 50 resonator 28. The latter is preferably made of a high conducting metal, such as copper, although it may also be made of Invar and coated on its interior surface with silver or copper. The cavity resonator 28, together with the tube 2, may 55 be placed within a temperature controlled con-

tainer 34 provided with thermostatically operated heaters and fans so as to maintain the temperature of the system constant and thereby enhance frequency stability.

As a further method of frequency control, a loop 36 may be provided for picking up some of the energy within the cavity resonator and this high frequency energy may be frequency divided by a frequency divider 38 and fed to a detector 40. The detector 40 is also fed with constant frequency oscillations from a crystal controlled oscillator 42 which, preferably, is temperature controlled. If desired, of course, the output of the crystal oscillator may be frequency multiplied by a suitable frequency multiplier before being fed into the detector 40.

The beat frequency resulting from action of detector 40 upon the waves fed to it from oscillator 42 and divider 38 is fed to a coil 43 and thence to a pair of off-tuned circuits 44, 46 having over-lapping resonance curves. The frequency discriminator system consisting of off-tuned circuits 44, 46 may also be mounted within a temperature controlled chamber 48. The outputs of discriminator circuits 44, 46 are fed to detectors 50, 52 connected in opposition across resistor 54. When the system is operating at its proper frequency, there will be no voltage drop across resistor 54. However, with departure in frequency of the oscillator from that for which the beat frequency from 40 lies at the cross-over point of the characteristics of circuits 44, 46, a voltage drop will be established across resistance 54 and this voltage is fed through conductors 56 to a resistor 58 in series with the grid supply source 24. The voltage then injected into resistor 58 is of such sense and magnitude as to change the frequency of the oscillator in the direction tending to reduce the voltage drop across resistor 54.

The frequency controlling voltage may be fed, if desired, into the anode circuit by tapping conductors 56 to resistor 60. Such an arrangement is shown in Figure 4.

The output of the oscillator may be modulated by means of a voice microphone or other suitable pick-up device 64 whose output is amplified by amplifier 66. The output of 66 may be inserted in series with the resistor 68 in the grid lead 20 as illustrated in Figure 1 of my parent application, now U. S. Patent No. 2,337,214, or, as illustrated, the output of amplifier 66 may be fed to the plate 6 by connection of conductors 70 to resistance 60. By appropriately controlling the injected modulation voltages, the output of the oscillator will be frequency modulated and substantially free of amplitude modulation.

The oscillator of Figure 2 is similar in construction and operation to that shown in Figure 1 with the exception that the anode 6 has been replaced by a cathode 7 heated by heater 9 and energized by transformer 11. Variable negative voltages from sources 13 and 15 may be provided for subjecting the cathodes 4, 7 to initial negative potentials with respect to ground. Also in Figure 2 the inductance of the grid conductor 20 may be tuned out, at the operating frequency, by the series tuning condenser 22.

As shown diagrammatically in Figure 3 the grid may be made in the form of two perforated or woven metal discs 31, 33. The resonator may then occupy the position shown diagrammatically at 35.

In all of the modifications shown, the cavity resonator may be moved along the tube for optimum operation. For example, it is not essential

that the grid be symmetrically disposed with respect to the gap in the cavity resonator, but rather the entire resonator, if desired, may be arranged so that the gap is unsymmetrical to the grid or entirely to either side thereof. Thus, for example, in Figure 4 such an arrangement is shown where the grid 8 is located between the cathode 4 and gap 30.

Also, the cathodes may be in the form of electron guns producing a concentrated, thin cylindrical stream of electrons or, if desired, the cathodes may be of the type to provide the emission of a hollow cylinder of electrons, which cylinder is concentric with the tube 2 and the cavity resonator 15. 28. Also, if desired, a variable unidirectional electro-magnet may be mounted outside of the cavity resonator and around the tube 2 to further control the cloud of electrons oscillating back and forth across the gap. Such an electro-magnetic 20 system will, of course, serve to prevent diffusion of the pulses or groups or clouds of electrons swinging back and forth through the grid 8.

Incidentally, as illustrated in Figure 1, time constant condensers 100 may be provided so that 25 the automatic frequency control operates only for slow drifts in frequency and does not wipe out the modulation frequency changes produced by the modulating system 64, 66.

The cavity resonators 28, shown in Figures 1 30 and 2, are preferably maintained at a small negative potential with respect to ground by means of source 110. This will serve to assist in the prevention of electron diffusion. However, the outer surface of the resonators may be connected directly to ground or, if desired, may be subjected to a positive D. C. potential with respect to ground, as shown in Figure 4.

In connection with Figures 1 and 4, bi-metallic strip 104 closes when the temperature within the 40 heat insulated chamber 34 becomes too high, thereby causing fan 106 to operate, in turn causing circulation of air around the oscillator and through openings in the chamber 34. When the 45 temperature is too low, strip 108 closes, energizing heater 111 from source 112. A similar fan and heater system may be placed within chamber 48.

In order to expedite temperature control, metal fins may be added to the outer surfaces of the 50 cavity resonators and/or small holes 120 may be provided in the walls of the cavity resonators so that air may circulate therethrough.

Having thus described my invention, what I claim is:

1. In combination, a space resonator having a gap, an electron discharge system for producing an electron flow across said gap, said system comprising an evacuated hermetically sealed container having therein an anode, a cathode and a grid, a circuit for heating said cathode, a connection for grounding said cathode, a connection for maintaining said grid at a positive potential with respect to ground, a circuit for maintaining said anode at a relatively negative potential with respect to ground, a circuit for superimposing upon said anode voltage variations corresponding to a desired signal whereby frequency modulated waves are generated within said space resonator and a utilization circuit coupled to the space within the resonator for removing frequency modulated waves therefrom and enabling the utilization thereof.

2. Apparatus as claimed in claim 1, characterized by the fact that said cathode is located to 75 one side of said gap, said anode is located on the

other side of said gap, and said grid is located to one side of said gap.

3. Apparatus as claimed in claim 1, characterized by the fact that said grid is arranged to one side of said gap and between said gap and said cathode.

4. In combination, a space resonator having a gap, a circuit for subjecting said resonator to a positive potential with respect to ground, an electron discharge system for causing an electron stream to flow past said gap, said discharge system comprising a grounded cathode and an anode subjected to a negative unidirectional potential with respect to said cathode, a circuit for varying the anode potential in accordance with modulating voltages whereby the currents flowing in said resonator are frequency modulated and a utilization circuit, coupled to the space within the resonator, for utilizing frequency modulated waves set up therein.

5. In combination, a space resonator having a gap, an electron discharge system for producing an electron flow past said gap, said system comprising an evacuated hermetically sealed container having therein an anode, a cathode and a grid, a circuit for heating said cathode, a connection for grounding said cathode, a connection for maintaining said grid at a positive potential with respect to ground, a circuit for maintaining said anode at a relatively negative potential with respect to ground, a circuit for maintaining said resonator at a positive potential with respect to ground, and a circuit for superimposing upon said anode, voltage variations corresponding to a desired signal whereby frequency modulated waves are generated within said space resonator.

6. Apparatus as claimed in claim 5, characterized by the fact that said cathode is located to one side of said gap, said anode is located on the other side of said gap, and said grid is located to one side of said gap.

7. Apparatus as claimed in claim 5, characterized by the fact that said grid is arranged to one side of said gap and between said gap and said cathode.

8. In combination, a space resonator having a gap, an electron discharge system for producing an electron flow across said gap, said system comprising an evacuated hermetically sealed container having therein an anode, a cathode and a grid, a circuit for heating said cathode, a connection for grounding said cathode, a connection for maintaining said grid at a positive potential with respect to ground, a circuit for maintaining said anode at a relatively negative potential with respect to ground, a circuit for superimposing upon said anode voltage variations corresponding to a desired signal whereby frequency modulated waves are generated within said space resonator, and a utilization circuit coupled to the space within the resonator for removing frequency modulated waves therefrom and enabling the utilization thereof, means for deriving from said resonator a portion of the waves generated therein, means for beating said derived waves with waves derived from a constant frequency generator to produce waves of intermediate frequency and means responsive to departures in frequency of said waves of intermediate frequency from a predetermined value to produce a controlling voltage and means for impressing said controlling voltage upon the anode of said discharge system to automatically frequency control the same.

9. Apparatus as claimed in claim 8 characterized by the fact that means are provided for fre-

quency dividing said portion of waves derived from said resonator for frequency controlling purposes before they are beat with the waves derived from said constant frequency oscillation generator.

10. In combination, a space resonator having a gap, an electron discharge system for producing an electron flow past said gap, whereby said resonator is excited and caused to have high frequency electrical waves set up therein, said discharge system including an electron emitting cathode, an anode and a grid, a circuit for beating said cathode to electron emitting condition, a circuit for subjecting said grid to a positive potential with respect to said cathode, a circuit for maintaining said anode at a negative potential with respect to said cathode, circuits responsive to waves in said cavity for producing a voltage which varies in polarity and magnitude when the frequency of the waves in said space resonator varies about a desired operating frequency, and a circuit for applying said voltage to said anode-cathode circuit for bringing the frequency of the waves set up in said cavity back to a desired operating frequency.

11. Apparatus as claimed in claim 10, characterized by the fact that a modulating circuit is provided for additionally subjecting said anode to cathode circuit to modulating voltages whereby the waves in said cavity are frequency modulated about a desired mean frequency of operation.

12. A high frequency, frequency modulation system comprising a space resonator having a gap, an electron discharge system for producing an electron flow past said gap in such a way as to set up high frequency oscillations in said resonator, said discharge system comprising an electron emitting cathode, a grid and an anode arranged in the order named along the axis of said gap, a circuit for subjecting said grid to a positive potential with respect to said electron emitting cathode, a circuit for subjecting said anode to a negative potential with respect to said electron emitting cathode, instrumentalities utilizing a portion of the waves set up in said resonator for producing a voltage which varies in polarity and magnitude according to departures in frequency of the waves in said resonator about a desired frequency of operation, means for applying said voltage to said anode and with respect to said cathode in such a way as to maintain the frequency of oscillations generated within said resonator at substantially a constant mean frequency, and means for subjecting said anode to a variable modulating voltage with respect to said cathode so as to frequency modulate the waves within said cavity resonator, and an output circuit coupled to said cavity resonator for deriving frequency modulated waves therefrom.

13. Apparatus for producing frequency modulated waves comprising a metallic space resonator having a gap, an electron discharge system for producing oscillations of electrons past said gap, said discharge system comprising a grounded cathode, an anode, a circuit for subjecting said anode to a negative unidirectional potential with respect to ground, a grid at the side of the gap nearest the cathode, a circuit for subjecting said grid to a positive potential with respect to ground whereby electrons attracted from the cathode pass through said grid and oscillate across said gap, a circuit for varying the voltage of said anode in accordance with signal control potentials whereby the wave energy set up within said space

resonator is frequency modulated, and a utilization circuit for deriving and utilizing frequency modulated waves from said metallic space resonator.

14. Apparatus for producing frequency modulated waves comprising a metallic space resonator having a gap, an electron discharge system for producing oscillations of electrons across said gap, said discharge system comprising a grounded cathode located on one side of said gap, an anode located on the opposite side of said gap, a circuit for subjecting said anode to a negative potential with respect to ground, a grid located adjacent the gap and at the side thereof nearest the cathode, a circuit for subjecting said grid to a positive potential with respect to ground whereby electrons pass through said grid and across said gap, and a circuit for varying the voltage on the anode in accordance with signals whereby wave energy set up within said metallic space resonator is frequency modulated, and a utilization circuit coupled to said resonator for deriving therefrom and utilizing frequency modulated waves set up within the space within the metallic resonator.

15. Apparatus for producing frequency modulated waves comprising a metallic toroidal space resonator having an annular gap at its inner periphery, an electron discharge system for producing oscillations of electrons across said gap, said discharge system comprising a cathode, a grid and an anode mounted within an evacuated space, the cathode and anode being located on opposite sides of the gap, the grid extending across the gap and lying in a plane to one side of said gap nearest the cathode, a direct current circuit connected between said cathode and ground, a direct current circuit connected between said anode and ground, said direct current circuits serving to maintain said anode at a negative potential with respect to said cathode, a direct current circuit connected between said grid and cathode serving to maintain said grid at a positive potential with respect to said cathode, a source of modulating potentials, a circuit for injecting said modulating potentials in the circuit between said anode and cathode whereby frequency modulated waves are set up in said metallic space resonator which are substantially free of amplitude modulation, and an output circuit coupled to said space resonator for deriving therefrom frequency modulated waves.

16. Apparatus for producing frequency modulated waves comprising a metallic toroidal space resonator having an annual gap at its inner periphery, an electron discharge system for producing oscillations of electrons across said gap, said

discharge system comprising a cathode, a grid and an anode mounted within an evacuated space, the cathode and anode being located on opposite sides of the gap, the grid extending across the gap and lying in a plane to one side of said gap nearest the cathode, a direct current circuit connected between said cathode and ground, a direct current circuit connected between said anode and ground, said direct current circuits serving to maintain said anode at a negative potential with respect to said cathode, a direct current circuit connected between said grid and cathode serving to maintain said grid at a positive potential with respect to said cathode, a detector, a circuit for feeding high frequency waves derived from said metallic space resonator and from another circuit carrying high frequency waves to said detector in order to produce waves of beat frequency in the output circuit of said detector, a discriminator-rectifier system coupled to the output circuit of said detector, said discriminator-rectifier circuit producing frequency controlling voltages, and a circuit for applying said frequency controlling voltages to the anode, cathode circuit of said electron discharge system.

17. Apparatus as claimed in claim 16 characterized by the fact that there is also inserted in said anode, cathode circuit modulating potentials whereby the waves generated in the space resonator are frequency modulated and substantially free of amplitude modulation.
